ABSTRACT OF THE DISCLOSURE

A detergent containing alkaline salts of organic, aliphatic and/or aromatic carboxylic acids and/or anhydrides of the same with one or several carboxylic groups. These salts replace in the detergent previously used phosphates which caused a eutrophication and endangered the ecology.

BACKGROUND OF THE INVENTION

The present invention relates to a washing dish-washing and cleaning detergent in the shape of powders, granules or pastes or liquids, the phosphates previously used in such a detergent being completely or partly replaced by chemicals which are more suitable from the eutrophic point of view.

The purpose of the phosphates in detergent compositions is to soften the water and to keep the hardening agents in the water in solution. Further, the phosphates have a certain dispersion effect on the dirt particles and improves the effects of the tensides in certain respects.

The phosphates form nutrient salts for the watercourses and when waste water is discharged into such watercourses, this results in overnutrition with an increased propagation of algae and a filling as a result (eutrophication). For this reason it is important to keep the phosphate contents as low as possible or to replace the phosphates completely in detergent compositions. In the detergent industry one has tried to accomplish this by introducing nitrilotriacetates (NTA) and replacing large parts of the phosphates therewith. As the decomposition of NTA in recipients and purifying plants is not completely known and the watercourses thereby are fed with nitrogen and nitrogen compounds, also NTA increases the algae growth why this solution of the eutrophication problem still is unsolved. Further, one does not know anything about the reactions between trace elements in natural watercourses and NTA.

SUMMARY OF THE INVENTION

The present invention relates to detergent compositions which contain alkaline salts of aliphatic and aromatic carboxylic acids and/or their anhydrides having as a maximum eight carbon atoms in the hydrophobic part or having one or several carboxylic groups or the free acids in a mixture with the alkaline salts of inorganic acids, e.g. carbonates and silicates. In order to improve the effect of said carboxylic acid salts it has turned out to be suitable to add multivalent higher alcohols up to an amount of 25%, preferably 0.5–8% as calculated on the quantity of said salts. Said acids are used because they contain only

2

carbon, hydrogen and oxygen besides alkaline metals. No eutrophication of the watercourses occurs as the decomposition products will essentially comprise carbon acid and water.

DETAILED DESCRIPTION OF THE INVENTION

The carboxylic acids which should preferably be used according to the invention are the following aliphatic acids: lactic acid, acetic acid, tartaric acid and citric acid, and the following aromatic acids: benzoic acid, phthalic acid and tri-, tetra-, penta- and hexa-carboxylic acids and their alkaline salts. However, the invention is not restricted to the acids enumerated in the foregoing but also other carboxylic acids which are not dangerous from toxicologic point of view may be used. One condition is of course that they could be accepted from water care point of view. They must also give a satisfactory washing result.

It has turned out in practice that acids with several COOH-groups give the best results in surface washing and at the same time many of these acids are toxicologically and allergologically undangerous and do not endanger water care. Several of these carboxylic acids occur in nature and form so to say a natural component of the plants and animals.

The anionic, double-ionic or nonionic tensides which may be present in the detergents according to the invention contain in their molecule at least one hydrophobic group having 8–30 carbon atoms and a group making them water soluble, this group being of anionic or non-ionic character. As anionic active detergent soaps, sulphonates and sulphates are of importance. Also phosphate tensides could be used. The sulphonates may comprise alkylaryl sulphonates, alkyl sulphonates, alkene sulphonates and oxyalkane sulphonates. Also sulphonated esters may be used. The sulphates may comprise e.g. alkylene sulphate, fatty alcohol ether sulphate, sulphated amides of fatty acids, sulphated monoglycerides, sulphating products of ethoxylated and/or propoxylated fatty alcohols, alkyl phenols, fatty acid amines, etc. Sulphonates of fatty acid esters of oxethane sulphonic acid and dioxypropane sulphonic acid, fatty alcoholic esters of lower aliphatic and aromatic thiomonoo- and dicarboxylic acids as well as condensation products of fatty acids with aminoethane sulphonic acids may be used. Synthetic capillary active carboxylates and condensation products of fatty acids with aminocarboxylic acids or with protein hydrolysates as well as phosphate esters of fatty alcohols and fatty acids may be used.

As nonionic tensides one may use e.g. alkyl phenol, fatty alcohol, alkyl amino, fatty acid, fatty acid alkylol amide fatty amide polyglycolethers, phosphate esters of ethoxylated fatty alcohols, block polymerisates of ethylene oxide and propylene oxide etc.

Also amphoteric tensides may be used such as imidazoline derivatives of fatty acids, carboxybetaines, compounds with the phosphoric acid groups in the acid rest or with sulphonic or sulphuric acid groups.

Foam stabilizers or foam inhibitors as well as corrosion inhibitors may be included and so may dirt carrying substances, optic brightening agents, perfumes, bactericides,

enzymes, dyes and water. Also different types of bleaching agents containing oxygen or chlorine and activators and stabilizers belonging thereto.

In order to improve the effect of the carboxylic acid salts there is added a multivalent higher alcohol in an amount up to 25%, preferably 0.5-8% as calculated on the quantity of said salts. The multivalent alcohols are selected from the group consisting of sorbitol, mannitol, pentaerythritol, trimethylol propane, trimethanol ethane, hexanetriol and butane triol.

As a conclusion it could be said that all tensides and aids used in connection with detergents and cleaning agents may be combined with the principle of the present invention and that the above enumeration is not to be considered as any restriction whatsoever.

The following examples are intended to illustrate the invention:

EXAMPLE 1

Large-scale detergent, powder		Parts
Dodecylbenzene sulphonate, calculated as containing 100%	6	
Alkylphenolic polyglycol ether, turbidity point 70-74° C.	5	
Fatty acid diethanol amide	1	
Na-toluene sulphonate	2	
Sodium soap	6	
Sodium perborate	20	
Sodium acetate	10	
Sodium citrate, 5½ cryst. water	20	
Sodium tripolyphosphate	5	
d-Sorbitol	4	
Sodium silicate, cryst.	10	
CMC, perfume, opt. brightening agent, enzymes, and water	11	

EXAMPLE 2

Large-scale detergent, granules		Parts
Fatty alcohol polyglycol ether having 30 mols EO (ethylene oxide)	12	
Tallow fatty alcohol	2	
Cumol sulphonate	3	
Na-adipate	3	
Na-K-tartrate	7	
Na-acetate	10	
Calcined soda	20	
Na-bicarbonate	10	
Na-percarbonate	15	
Na-silicate	10	
CMC, perfume, opt. brightening agent, Mg-silicate, enzymes, and water	8	

EXAMPLE 3

Detergent for ordinary washing, sprayed		Parts
Na-dodecyl benzene sulphonate	10	
Fatty alcohol polyglycol ether	5	
Xylene sulphonate	7	
Sodium soap, 80%	2	
Phosphate ester of ethoxylated fatty alcohol	2	
Na-perborate	15	
Na-citrate	30	
Mannitol	5	
Na-silicate	10	
EDTA or NTA	3	
Na-salt of benzene tetracarboxylic acid	2	
CMC, opt. brightening agent, Mg-silicate	9	

EXAMPLE 4

Small-washing detergent, gran.

	Parts
5 Alkylbenzene sulphonate, 50%	12
Fatty alcohol polyglycol ether	6
Thiosuccinic acid semiester of fatty acid polyglycol ether, Na-salt	3
10 Coconut fatty acid monoethanol amide or fatty acid amide polyglycol ether	2
Na-silicate	6
Mannitol	2.5
Na-citrate	21
15 Benzene hexacarboxylic acid	3.5
Gran. soda	10
Sesquicarbonate	14
Sodium sulphate calc.	13
CMC, opt. brightening agent, perfume, water	7

EXAMPLE 5

Pre-washing detergent, powder, gran.

	Parts
20 Alkylsulphate, Na-salt	4
Lauric acid monoethanol amide thiosuccinic semiester, Na-salt	2
25 Fatty acid polyglycol ester	4
Soda gran.	20
Sodium bicarbonate	20
Na-disilicate	15
Na-acetate	20
30 Potassium biphthalate	5
Pentaerythrite	4
CMS, opt. brightening agent, enzymes, water	6

EXAMPLE 6

Liquid washing and cleansing agent

	Parts
Mixture of alkane and alkene sulphonates	7
Dialkyl phenolpolyglycol ether	3
40 Undecylene acid monoethanol amide thiosuccinic acid semiester, Na-salt	3
Fatty acid aminoxide	2
Pine-oil	3
Ethyldiglycol	3
45 Sodium lactate	10
Sorbitol	2
Water, perfume, dyes, ammonia etc.	67

EXAMPLE 7

Dish-washing machine detergent

	Parts
Polypropylene-ethylene oxide-addition product	3
Sodium alkyl polyglycol etherphosphate	3
Na-acetate	25
55 Na-sulphate	25
Na-citrate	30
Perfumes, dyes, bactericides, water	14

EXAMPLE 8

Washing and cleansing paste

	Parts
Fatty acid imidazoline derivate, 50%	10
Succinic acid-2-ethyl hexyl monoester	3
65 Undecylene acid monoethanol amide	3
Fatty acid condensation product with methyl taurine	16
Glycol derivate	7
Na-citrate	11
1,4-butane dicarboxylic acid	2
70 CMC	3
Water	45

What I claim is:

1. A detergent composition consisting essentially of: a water-soluble surface active agent have 8 to 30

carbon atoms in the hydrophobic group thereof, selected from the group consisting of an anionic wetting agent, a nonionic wetting agent, an amphoteric wetting agent and mixtures thereof in an amount of from about 10 to about 32 parts per 100 parts of composition;

an alkaline salt of a carboxylic acid selected from the group consisting of lactic acid, acetic acid, tartaric acid, citric acid, butane dicarboxylic acid, adipic acid, benzoic acid, phthalic acid, benzene tricarboxylic acid, benzene tetracarboxylic, benzene pentacarboxylic, benzene hexacarboxylic acid and mixtures thereof, said alkaline salt being present in an amount of from about 10 to about 30 parts per 100 parts of composition,

a polyhydric alcohol selected from the group consisting of sorbitol, mannitol, pentaerythritol, trimethylol propane, trimethylol ethane, hexanetriol and butane triol, said polyhydric alcohol being present in said composition in an amount of 0.5% to 25% by weight of the salt of said carboxylic acid thereof.

2. The detergent composition of claim 1 wherein said surface active agent is an anionic wetting agent.

3. The detergent composition of claim 2 wherein said surface active agent is a sodium soap.
